UNITED STATES PATENT OFFICE.

WILLIAM HENRY KENYON, OF ACCRINGTON, ENGLAND, ASSIGNOR TO ENTWISLE & KENYON LIMITED, OF ACCRINGTON, ENGLAND.

CARPET SWEEPER.

Application filed October 22, 1923, Serial No. 670,039, and in Great Britain November 7, 1922.

This invention relates to combs or clearers for the rotary brushes of carpet sweepers such as described in the specification of British Patent No. 26,003 of 1913 for clearing or removing from the brush, hairs, fibres or threads which have a tendency to lap round the brush.

In the specification No. 26,003 of 1913 there is described an appliance attached to a block or bar affixed to the underside of the casing with depending blades or teeth to enter between the bristles of the brush as it rotates to engage with and sever any hairs or threads lapped thereon.

We find that as there is a certain space between these blades it is possible for hairs to lap and collect between them which are not removed and the object of the present invention is to provide for the more effective clearing of the brush.

According to the invention in a stationary plate or comb which is rigidly affixed in position the blades are stamped from the centre of a metal strip and the depending blades are disposed in an inclined or diagonal direction instead of at right angles to the longitudinal axis of the plate or comb thus one edge of each blade will act upon a specific part of the periphery of the brush when the latter rotates in one direction and the other edge of the blade upon a different part of the periphery when the brush rotates in the reverse direction ensuring that each blade will clean a greater area of the surface of the brush and the sides of the blades will assist in detaching the broken threads or hairs from the bristles.

The invention will be fully described with reference to the accompanying drawings.

Fig. 1 is a longitudinal section through the carpet sweeper showing the improved clearer C.

Fig. 2 is a longitudinal section (enlarged) of the improved clearer C.

Fig. 3 is a plan of same from the underside.

Fig. 4 is an end elevation.

Fig. 5 is a perspective view of separate claw D for securing the clearer C in position.

Fig. 6 is a plan of same in position on clearer C.

Fig. 7 is a longitudinal section showing same in position.

The sweeper case A with a block or bar E to retain the clearer C and the brush B are of ordinary form or construction.

The improved clearer C has the blades c placed at an inclination to the longitudinal axis of the clearer. They are preferably stamped out of a strip of steel and the blades may all be inclined in one direction as shown in Fig. 6 though preferably some are inclined to the right and some are inclined to the left as shown in Figs. 2 and 3.

The clearer C may be affixed to the block E on the underside of the case A or by a bracket D as described and claimed in our concurrent application. The bracket D may be stamped integral with the clearer C and bent up over the block E as in Figs. 2 and 3 or it may be separate with a diagonal slit d to engage one of the blades c at the end of the clearer C as in Figs. 5 to 7, or the bracket may be soldered or brazed to the clearer and secured to the case A.

What I claim as my invention and desire to protect by Letters Patent is:—

In a carpet sweeper having a case and a horizontal cylindrical brush, a clearer positioned above said brush and provided with blades to engage the periphery of the brush, said blades extending downwardly from the centre of a strip of metal and set at an inclination to the longitudinal axis thereof whereby one edge of each blade will contact with a specific part of the brush periphery when rotating in one direction and the other edge with a different part of the brush periphery when rotating in the reverse direction.

In testimony whereof I have hereunto set my hand.

WILLIAM HENRY KENYON.
